United States Patent Office

Des. 184,906
Patented Apr. 21, 1959

184,906

VENDING MACHINE

Lyle M. Becker, Brillion, Wis.

Application September 29, 1958, Serial No. 52,806

Term of patent 7 years

(Cl. D52—3)

FIG. 4.

FIG. 2.

Fig. 1 is a front view of a vending machine showing my new design;

Fig. 2 is a top plan view thereof;

Fig. 3 is a side elevational view; and

Fig. 4 is a rear view.

I claim:

The ornamental design for a vending machine, substantially as shown.
